CLAIM

The ornamental design for a hair dryer, as shown and described.

DESCRIPTION

1. Hair dryer

Fig. 1.1 is a front view of a hair dryer showing our new design;

Fig. 1.2 is a back view thereof;

Fig. 1.3 is a left view thereof;

Fig. 1.4 is a right view thereof;

Fig. 1.5 is a top view thereof;

Fig. 1.6 is a bottom view thereof;

Fig. 1.7 is a front left perspective view thereof.

The broken lines depict parts of the hair dryer that form no part of the claimed design.
